UNITED STATES PATENT OFFICE.

ANDREW J. LOCKIE, OF ROCHESTER, MINNESOTA, ASSIGNOR OF ONE-HALF
TO THOMAS H. TITUS, OF SAME PLACE.

PAD FOR HORSES' HOOFs.

SPECIFICATION forming part of Letters Patent No. 241,870, dated May 24, 1881.

Application filed December 23, 1880. (No model.)

To all whom it may concern:

Be it known that I, ANDREW J. LOCKIE, a citizen of the United States, residing at Rochester, in the county of Olmsted and State of Minnesota, have invented certain new and useful Improvements in Pads for Horses' Hoofs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention is an improvement on the patent previously granted to A. J. Lockie, the present applicant, on the 1st of June, 1880, and numbered 228,262.

It consists in providing the throat of the 20 pocket-sheet with a dirt-excluding strip; also, in adapting the latter to serve as a strengthening and packing-confining device; and, finally, in the construction and combination of the various parts hereinafter set forth and 25 claimed.

In the accompanying drawings, Figure 1 represents a perspective view of a horse's hoof and shoe with my pad applied thereto. Fig. 2 represents in detail a view of the inner side of 30 the pocket-sheet provided with one form of my present improvement. Fig. 3 represents a similar view of a pocket-sheet and horseshoe having another form of said improvement applied thereto. Fig. 4 represents a view of a leather 35 blank provided with my dust-excluding strip and adapted to be formed into a pocket-sheet, and Fig. 5 represents a vertical section.

A designates a horseshoe having lugs *a a*; B, a pocket-sheet having a pear-shaped pocket; B'; C, a pad of sponge, which fits into 40 and fills said pocket; D, a stiffening piece, and E a metallic brace, all substantially as described in said prior patent.

The stiffener D may, of course, be applied 45 on either side of sheet B; but it has been shown, for convenience, on the underside thereof. The brace E is serviceable, but not indispensable.

These pads, as heretofore made and applied,

have been found subject to one serious defect—namely, the admission of dust, dirt, and foreign matter generally to the interior of the pad, and between it and the horse's foot, through the neck *b* of sheet B. To prevent this I employ a strip or plate, F, of leather, metal, or any other suitable material, which is attached either to pocket-sheet B alone, as shown in Fig. 2, or to lugs *a a* of shoe A, as shown in Fig. 3, by means of rivets or other fastenings, that pass through said pad-sheet and stiffening piece D. In the latter case the length of the strip F is necessarily increased, and it is preferably of rigid metal. When attached to the pocket-sheet alone, the strip F need not be longer than the width of neck *b*. In either 65 case the said strip closes the opening of said neck, and thereby prevents the entry of dirt or other foreign matter to the interior of the pad. It also acts as an additional stiffener, and insures the retention of the packing within 70 its pocket. The bracing action is particularly efficacious when the piece F is made of rigid material and attached to lugs *a a*, as stated. It then strengthens the shoe as well as the pad.

Having thus fully described my invention, 75 what I claim as new, and desire to secure by Letters Patent, is—

1. In combination with a flexible pad-sheet having a packing-pocket formed therein, a strap or plate secured to said sheet on the upper or inner face thereof, and serving to retain the packing within said pocket, to brace the said pad, and to exclude dirt, substantially as set forth.

2. In combination with pad-sheet B, having a packing-pocket, the stiffening-piece D on the bottom of said pad-sheet, and the strip or plate F on the upper or inner side thereof, said strip or plate serving to exclude dirt, to retain the packing, and to brace the pad-sheet.

3. In combination with the shoe A, having on its inner edges or sides the perforated lugs *a a*, the pad-sheet B, formed with a pocket to receive packing, and the strip or plate F, arranged across the mouth of said pocket on 90 the inner side of said sheet, said sheet and strip both being secured to said lugs by the same fastenings.

4. In combination with shoe A, having lugs
a a, the pad B, having pocket B', for the re-
ception of packing, the stiffening-piece D on
the under side of said pad-sheet, and the strip
5 F on the upper or inner side of said pad-sheet,
said parts B D F being secured to said lugs
by the same fastenings.

In testimony whereof I affix my signature
in presence of two witnesses.

ANDREW J. LOCKIE.
